UNITED STATES PATENT OFFICE.

ARTHUR G. ROGERS, OF MERIDEN, CONNECTICUT, ASSIGNOR TO C. ROGERS & BROS., OF SAME PLACE.

DESIGN FOR A HANDLE FOR SPOONS, &c.

SPECIFICATION forming part of Design No. 26,969, dated April 27, 1897.

Application filed March 29, 1897. Serial No. 629,869. Term of patent 3½ years.

To all whom it may concern:

Be it known that I, ARTHUR G. ROGERS, of Meriden, in the county of New Haven and State of Connecticut, have invented a new 5 Design for Handles of Spoons, Forks, &c.; and I do hereby declare the following, when taken in connection with the accompanying drawing and the letters of reference marked thereon, to be a full, clear, and exact description of the same, and which said drawing constitutes part of this specification and represents a face view of handle illustrating my design.

This invention relates to a design for the 15 handles of spoons, forks, &c.; and it consists in the configuration and ornamentation as hereinafter described and shown in the accompanying illustration.

As shown in the drawing, the outer end of 20 the handle terminates in a trefoil A, on opposite sides of which are outwardly and downwardly turned scrolls B. The edges of

the handle below the scrolls B are ornamented by inwardly-curved scrolls C and outwardly-curved scrolls D, the said scrolls C and D being connected by a foliated ornamentation D, inclosing a plain panel F. Below the scrolls D the edges of the handle taper inward and are edged by long narrow scrolls G, beyond which are short reversely-curved scrolls 30 H, which merge into the edge of the body I.

Having fully described my invention, what I claim, and desire to secure by Letters Patent, is—

The design for handles of spoons, forks, 35 &c., as herein shown and described.

In testimony whereof I have signed this specification in the presence of two subscribing witnesses.

ARTHUR G. ROGERS.
